ABSTRACT

A constant voltage regulators in which the output current is limited by a series impedance and the output voltage is shorted for the remainder of each half cycle by the operation of a solid state switching device whose operation is initiated when the time integral of the output voltage taken with zero initial conditions at the start of each half cycle reaches a predetermined magnitude.

CONSTANT VOLTAGE TRANSFORMERS

This invention relates to constant voltage regulators such as are often known as constant voltage transformers.

A known form constant voltage REGULATOR essentially comprises a series current limiting impedance (usually an inductor) and a parallel saturable inductor which is so arranged as to saturate when the time integral of the voltage across it has reached a predetermined value thereby shorting together the output terminals of the transformer. These functions are usually incorporated in a specially constructed transformer. Two of the many disadvantages inherent in such a constant voltage regulator are a) it is often heavier than is desirable due to the inherent weight of the essential saturating inductor and b) particularly at high frequency, for example 400 cycles, it is undesirably inefficient due to hysterises and eddy current losses in the inductor's core.

In a constant voltage regulator in accordance with the invention the output current is limited by a series impedance and the output voltage is shorted for the remainder of each half cycle by the operation of a solid state switching device whose operation is initiated when the time integral of the output voltage taken with zero initial conditions at the start of each half cycle, reaches a predetermined magnitude. The constant voltage function is thus separated from the transforming function. An advantage of such a constant voltage regulator lies in the saving in weight which may be obtained by substituting a solid state switching device for the saturating inductor of known forms of a constant voltage regulator. Further there are no hysterises or eddy current losses associated with such a solid state switching device which may pass substantially no leakage current when in its off condition and which may absorb substantially no power when in its on condition.

The operation of the solid state switching device is preferably initiated by firing means arranged to full wave rectify the output voltage, the rectified voltage being integrated, from a predetermined initial condition of the start of each half cycle, by a serially connected resistor and capacitor, threshold dependant solid state trigger being so connected as to initiate the operation of the solid state switching device when the voltage across the capacitor reaches a predetermined value. This particular construction is advantageous in that since the output voltage is rectified and since the integration is carried out from a predetermined initial condition at the start of each half cycle the circuit has no memory of the preceding half cycle. In contrast, in the above mentioned known forms of constant voltage regulators, after saturating on one half cycle the saturating inductor retains a high level of flux in its core and if the supply is then cut off and reinitiated in the same polarity as that of the last half cycle before it was switched off the inductor saturates almost immediately with the result that a large current is drawn from the supply dictating unsafe fuse ratings or frequent fuse replacement. Further it will be appreciated that the constant voltage regulator of the invention may be used with a uni-directional periodic supply. In contrast the known forms of constant voltage transformer may not be so used since the saturating inductor would remain permanently in the saturated condition.

The solid state switching device preferably comprises a triac or two controlled rectifiers connected anti-parallel. An advantage of this arrangement is that the firing means need only provide the firing pulse it not being necessary to maintain the signal to the solid state switching device in order to keep it conducting up to the end of each half cycle.

The firing means preferably includes active elements which have no primary power source other than the rectified voltage.

Further the firing means preferably include means to ensure the capacitor is in a discharged state at the end of each half cycle, the predetermined initial condition at the start of each half cycle in this case being zero.

One embodiment of the invention will now be described by way of example with reference to the accompanying drawings in which:

FIG. 1 is a general circuit diagram of a constant voltage regulator in accordance with the invention;

FIG. 2 is a more detailed circuit drawing of the solid state switching device and its firing means;

FIG. 3 is a general circuit diagram of a modified constant voltage regulator in accordance with the invention.

Referring firstly to FIG. 1 it will be seen that the constant voltage regulator has input terminals 2 for connection to an alternating voltage supply or to a periodic voltage supply, and output terminals for connection to a load. Serially connected between the input and the output is an impedance 6, in this case an inductor. Connected between the two output terminals is a solid state switching device T_5 , in this case a triac. Connected in parallel with the triac T_5 and to its gate is a firing circuit 8. In operation the output current is limited by the series inductor 6 and the firing circuit 8 acts to fire the triac so that it shorts together the output terminals for the remainder of each half cycle when the time integral of the output voltage, taken with zero initial conditions at the start of each half cycle, reaches a predetermined magnitude. Thus the rectified means of the output voltage appearing at the terminals 4 is substantially independant of variations in the voltage supply at the end of terminals 2 of variations in the load impedance connected to terminals 4.

Referring now to FIG. 2 it will be seen that the voltage appearing across terminals AB of the firing circuit 8 (i.e. the output voltage) is full wave rectified by diodes D_1 , D_2 , D_3 and D_4 so providing a positive and a negative supply rail 10 and 12 respectively. The rectified voltage is integrated by a resistor capacitor arrangement RV_1 , R_1 and C_1 , the rate at which capacitor C_1 charges being adjustable by means of the variable resistor RV_1 . The voltage across capacitor C_1 thus represents the time integral of the voltage between the terminals A and B. The arrangement is such that the voltage across the capacitor which represents the predetermined magnitude of the predetermined time integral of the output voltage is small compared with the voltage between the terminals A and B. This voltage is determined by a serially connected resistor and Zener diode chain R_3 and ZD_1 to the junction of which is connected the emitter of an N.P.N. transistor whose base is connected to the junction between capacitor C_1 and its series resistance R_1 .

When capacitor C_1 has charged to a sufficiently high voltage transistor T_2 conducts causing transistors T_3 and T_4 of a regenerative switch arrangement rapidly to conduct. Initially the current through the regenerative switch T_3 , T_4 passes through capacitor C_2 . However, when the voltage across capacitor C_2 has built up sufficiently the current is conducted through a Zener diode ZD_2 which is connected in parallel with capacitor C_2 . The said current is divided between resistor R_6 and a path through a primary winding of a transformer TR_1 and through the base emitter junction of a transistor T_1 . The step of current so passing through the primary winding of transformer TR_1 induces in its secondary winding a voltage pulse which fires the triac T_5 through a resistor R_9 . The current also acts to cause transistor T_1 to conduct so discharging capacitor C_1 .

In order to ensure that there is a sufficiently low impedance voltage source for the above described operations to take place, even towards the end of a half cycle when the magnitude of the rectified voltage is diminishing, a capacitor C_3 is connected across the regenerative switch arrangement T_3 , T_4 and is charged during each half cycle from a potential divider R_7 and R_8 and diode D_6 to a voltage limited by a Zener diode ZD_3 .

At the end of each half cycle the triac T_5 ceases to conduct and must be re-fired during the next half cycle.

In order to ensure that the regenerative switch T_3 , T_4 turns off at the end of each half cycle capacitor C_3 is provided with a discharge path through the emitter to base junction or transistor T_3 in parallel with resistor R_4 and through diode D_5 so that when the voltage between the terminals A and B has reduced sufficiently for diode D_5 to be forward biased the capacitor C_3 begins to discharge. When the capacitor C_3 is discharged to a voltage which is lower than the voltage stored on the capacitor C_2 the regenerative switch T_3 , T_4 turns off.

Further if due to an exceptionally low output voltage the capacitor C_1 does not charge sufficiently to trigger triac T_5 , when the capacitor C_3 begins to discharge through the resistor R_4 and the diode D_5 the voltage drop across the resistor R_4 so biases the base of transistor T_3 as to cause the regenerative switch T_3 , T_4 to conduct so firing triac T_5 and causing transistor T_1 to conduct and thus discharge capacitor C_1 . When the capacitor C_3 has discharged to a lower voltage than the voltage stored on the capacitor C_2 , regenerative switch T_3 , T_4 again cuts off. The capacitor C_1 is thus in a discharge state at the beginning of each half cycle.

It will be appreciated that the constant voltage regulator described will equally operate on a uni-directional periodic supply as on alternating supplies providing

that the periodic supply reduces to zero potential in each period long enough for T_5 to turn off.

An advantage of the above arrangement which will be apparent is that by adjusting resistor $RU1$ so as to vary the charging rate of the capacitor C_1 the output voltage of the transformer may easily be adjusted.

In the modified arrangement shown in FIG. 3, the triac is replaced by two control rectifiers T_{5a} and T_{5b} arranged in anti-parallel.

We claim:

1. A constant voltage regulator for a cyclic voltage supply comprising:
input terminals;
output terminals;
a current-limiting impedance connected in series between an input terminal and an output terminal;
a solid state latching switching device connected across the output terminals and initiatable to short the output terminals together, said switching device being of the type which unlatches each time the short circuit current therethrough falls to substantially zero;
re-settable integrating means for generating a signal dependent upon the time integral of the voltage across said output terminals;
threshold-dependent initiating means for initiating said switching device each time the magnitude of said signal exceeds a predetermined value; and
discharge path means, including actuatable switching means, for re-setting said integrating means each time the voltage across said output terminals falls to substantially zero, said discharge path means, when said switching means is actuated, having an impedance which resets said integrating means to the same initial condition each time said integrating means is reset.

2. A constant voltage regulator as claimed in claim 1 wherein said switching device comprises a triac.

3. A constant voltage regulator as claimed in claim 1 wherein said switching device comprises two controlled rectifiers connected anti-parallel.

4. A constant voltage regulator as claimed in claim 1 including full wave rectifying means connected across the output terminals, wherein the integrating means is so connected as to integrate the rectified output of said rectifying means.

5. A constant voltage regulator as claimed in claim 4 wherein the integrating means and the initiating means comprise active elements which have no primary power source other than the rectified voltage.
